UNITED STATES PATENT OFFICE.

EDGAR GIROD, OF RAYVILLE, LOUISIANA, ASSIGNOR OF ONE-THIRD TO
GERALD T. JONES, OF SAME PLACE.

PLOW.

SPECIFICATION forming part of Letters Patent No. 627,996, dated July 4, 1899.

Application filed September 12, 1898. Serial No. 690,757. (No model.)

To all whom it may concern:

Be it known that I, EDGAR GIROD, a citizen of the United States, residing at Rayville, in the parish of Richland and State of Louisiana, ⁵ have invented a new and useful Plow, of which the following is a specification.

My invention relates to improvements in plows; and the object that I have in view is to improve the means for joining the share ¹⁰ detachably to the moldboard and landside without the employment of bolts, screws, or rivets and to effect the wedging of the share firmly in place by the resistance of the soil to the implement.

¹⁵ A further object is to arrange the several elements in a way to secure a flush joint between the landside, the moldboard, and the share, and also to provide for locking the parts firmly together against tendency to accidental displacement in any direction.

With these ends in view the invention consists in the novel construction and arrangement of parts, which will be hereinafter fully described and claimed.

²⁵ To enable others to understand the invention, I have illustrated it in the accompanying drawings, forming a part of this specification, and in which—

³⁰ Figure 1 is an inverted or bottom plan view of a plow having a share constructed in accordance with my invention. Fig. 2 is an elevation looking at the landside of the plow. Fig. 3 is a longitudinal sectional elevation on the plane indicated by the dotted line 3 3 of Fig. 1. Fig. 4 is a detail horizontal section ³⁵ through the landside and the sole-flange of the share, the plane of section being indicated by the dotted line 4 4 of Fig. 2. Fig. 5 is a perspective view of the share detached from the moldboard and landside. Fig. 6 is a detail ⁴⁰ perspective view of a part of the landside and standard to show the crotch or seat for the reception of the sole-flange on the share.

Like numerals of reference denote like and ⁴⁵ corresponding parts in each of the several figures of the drawings.

The standard or stock 10 of a plow embodying my invention has its lower forward extremity reduced in width to produce the point ⁵⁰ 11, and this stock and the moldboard 12 are united in any way approved by those skilled

in the art. The landside 13 is arranged to overlap the lower part of the stock, and this landside is peculiarly constructed, as will presently appear, and is united to the pointed ⁵⁵ end 11 of the stock to form therewith a crotch or seat, as shown by Fig. 6. The handles 14 of the implement are tied together and united to the beam in a manner well understood by those skilled in the art, and the lower end of ⁶⁰ one handle is attached, as at 15, to the heel of the landside, while the corresponding end of the other handle is united to a lug 16 on the rear neutral face of the moldboard.

The front extremity of the landside 13 is ⁶⁵ formed with a downward and rearward sloping edge 17, and this sloping edge is beveled inwardly toward the pointed extremity 11 of the stock.

The share 20 is cast in a single piece, with ⁷⁰ a sole-flange 23, that protrudes beyond the rear edge of the share, which is designed to underlap the lower edge of the moldboard and produce a flush joint between the share and the moldboard. As is usual in the art, ⁷⁵ the share has a point 21 and the front cutting edge 22; but in lieu of making the point integral with the share, as herein shown, I may employ a separable or detachable point, which, however, I do not deem it necessary to illustrate. The sole-flange 23 of the share, which projects beyond the rear edge thereof, is arranged to overlap the pointed end 11 of the stock, and the projecting end of the sole-flange is peculiarly fashioned to fit snugly to ⁸⁰ the end of the landside, so that the sole-flange and the landside may interlock, and the faces and edges thereof will lie flush to avoid any protruding parts at the joint between the landside and the share. To attain this end, ⁸⁵ I form the projecting rear extremity of the sole-flange 23 with a sloping edge 24, that inclines downwardly and rearwardly at an angle corresponding to the edge 17 of the landside, and this sloping edge 24 of the sole-flange is beveled inwardly to correspond with the bevel 18 of the landside. It will thus be observed that the share has its sole-flange constructed to overlap the pointed end of the stock and to underlap the sloping and beveled ⁹⁰ edge of the landside when the share is properly fitted to the moldboard and stock, and

the face, as well as the edge, of the sole-flange lies flush to the corresponding parts of the landside.

On the under neutral face of the share are 5 cast the spaced lugs 25, having the beveled edges 25^a, and these lugs are spaced to form between their beveled edges a tapered key-seat 26. To lock the share to the moldboard, I resort to the employment of a tapering key 10 or wedge 27, which is arranged to fit snugly against the curved rear face of the moldboard and is provided with a longitudinal slot 29, through which passes the bolts 30, that are rigid with the moldboard. The key or wedge 15 is held on the under side of the moldboard by the nuts 31, which are screwed on the bolt to bear against the key, and the tapered working end of this key or wedge protrudes beyond the lower edge of the moldboard, so as 20 to fit into the key-seat formed by and between the beveled edges of the lugs on the share. The heel of this key or wedge has an offstanding flange 28, which provides a convenient means by which the key may be ad- 25 justed.

To remove the share from the plow, the key or wedge is driven out of the key-seat in the share, and the latter is then withdrawn from the moldboard, so as to disengage its sole- 30 flange from the crotch or seat at the juncture of the landside and stock. To replace the pointed share, it is adjusted for its rear edge to underlap the moldboard and to have the sloping and beveled heel of its sole-flange enter the crotch or seat of the landside and stock, so that the heel of said sole-flange will overlap the pointed end of the stock and will underlap the sloping and beveled front extremity of the landside, after which the wedge or 40 key is driven into the key-seat formed by the lugs on the share. The share is thus attached to the plow without the employment of bolts or their equivalents to hold it in place; but, on the contrary, the share of my invention is 45 interlocked with certain parts of the plow and secured in place by a key or wedge in a manner to have the share forced firmly into position by the resistance of the soil when the implement is in service. The parts are simple 50 in construction, to the end that the share may be cast in a single piece and the parts readily assembled together without finishing the same by hand. The share may be easily detached

and quickly applied by the farmer, and the absence of bolts to fasten the share expedites 55 the labor of attaching or detaching it.

Changes may be made in the form of some of the parts while their essential features are retained and the spirit of the invention embodied. Hence I do not desire to be limited 60 to the precise form of all the parts as shown, reserving the right to vary therefrom.

Having thus described the invention, what I claim is—

1. In a plow, the combination of a share 65 provided on its rear face with the spaced lugs having their opposing edges beveled and forming a dovetailed way, a moldboard, a slotted endwise-movable key curved to conform to the moldboard and fitted thereto in alinement 70 with the dovetailed way for adjustment into engagement with the lugs, and bolts fixed to the moldboard and fitting in the slots of the key to slidably hold the latter in place, substantially as described. 75

2. The combination, in a plow, with a mold- 80 board and a stock, of the landside provided with a sloping and beveled front extremity which laps the stock and forms therewith a seat or crotch, a share having its sole-flange provided with the sloping and beveled heel 85 which is fitted snugly to the sloping and beveled edge, of the landside, for the sole-flange to lie flush with the face of said landside, and means for fastening the share to the mold- 90 board, substantially as described.

3. In a plow, the combination with a mold- 95 board, and a stock having a pointed extremity, of the landside having the inclined and beveled extremity which is arranged to overlap the stock, a share having its sole-flange formed with a sloping and beveled heel and fitted to the end of the landside for the faces of the sole-flange and the landside to lie flush with each other, the beveled lugs on the rear 95 face of the share, and a key or wedge slidably confined on the moldboard and engaging with said lugs, for the purposes described, substantially as set forth.

In testimony that I claim the foregoing as 100 my own I have hereto affixed my signature in the presence of two witnesses.

ED. GIROD.
